MOTORER, OF STOCKHOLM, SWEDEN.

FUEL-INJECTOR.

1,112,877.

Specification of Letters Patent.

Patented Oct. 6, 1914.

Application filed April 26, 1910. Serial No. 557,781.

To all whom it may concern:

Be it known that I, SVEN WIGELIUS, engineer, a subject of the King of Sweden, and residing at Kaptensgatan 17, Stockholm, Sweden, have invented new and useful Improvements in Fuel-Injectors, of which the following is a specification.

The invention relates to a regulating device for gas motors and has for its object 10 to regulate the quantity of air introduced into the cylinder in such a manner that said quantity will increase when the volume of the cylinder will increase during the movements of the piston, while simultaneously 15 the velocity of the air will be very high in order to obtain an intimate mixture of air and fuel. This is attained according to the present invention by introducing the air through a channel, the cross-section 20 whereof is varied during the movement of the piston in such a way that the cross-section will increase when the cylinder volume increases. This is preferably attained by forming the air channel between a stationary tube-wall and a movable spindle, in 25 which case either the cross-section of the spindle or the inner diameter of the tube or both varies.

An embodiment of the invention is illustrated in the accompanying drawing in longitudinal section.

a indicates an outer tubular sleeve, into which the plug *b* is screwed.

c indicates an inner vertically movable tube and *d* the regulating spindle, which 35 is arranged in the channel formed by the parts *b* and *c*.

e is the air passage.

The regulating spindle is provided with 40 a shoulder edge *h* and tapers below this shoulder edge, which during the upward movement of the spindle moves into the part of the channel *e*, which increases in width 45 toward the top of the tube *c*. By the operation of the tapering spindle and the channel, the width of which increases from the shoulder edge *i* of the tube *c*, the air 50 channel will of course be varied by the relative movement of the parts *c* and *d*, and a greater or smaller quantity of air will thereby flow through this channel *e*. If the dimensions of the spindle and the 55 channel are selected properly and if the spindle is suitably moved, for instance by

means of cams, being in timed relation 55 which the engine, the quantity of the air introduced is regulated during each moment in such a manner that it corresponds entirely or nearly to the increase of the cylinder volume during the same time. 60

In order to obtain a very intimate mixing of the air and the fuel introduced, it is preferable that this fuel is introduced at or near that place of the channel, where its cross-section is the smallest and where 65 thus the speed of the current is the greatest. In the embodiment shown this is attained by introducing the fuel through the channel *f* into the annular space *g* between the lower end of the tube *c* and the upper end 70 of the plug *b*, the enlarged portion at the lower end of said tube *c* constituting a valve *k*, while the frusto-conical surface *k'* within the sleeve is acting as a valve seat for the same. Compressed air is introduced into the annular space *c'* through 75 the channel *j*, as well as through the passage *e*, while the fuel is introduced through the fuel part *f* into the annular chamber *g*. If the spindle *d* is raised, an annular 80 space surrounding the spindle is formed through which the compressed air is rushing into the cylinder and which, when the tube *c* is elevated, is in communication with the annular space *g*. The spindle *d* is 85 formed intermediate its ends with a shoulder *h* constituting a valve adapted to rest against the seat *i* of the tube *c*, when said spindle is elevated. In order to admit a generous quantity of air to the cylinder 90 during the forward movement of the piston, the cross-section of the annular air inlet channel must be increased during the upward motion of the spindle *d*. This is effected by tapering that part of the spindle 95 below the shoulder *h* as shown. It will be clear, that consequently during the up and downward movement of the spindle *d* the air inlet channel will be enlarged or decreased. The fuel is injected in the customary manner through the inlet *f* into the fuel chamber *g* which is alternately in communication with the space surrounding the spindle and with the fuel pump. The valve at the lower part of the tube *c* closely fits 100 to the spindle *d* and thus, when the fuel valve is closed, no hollow space is remaining, in which fuel may be retained which 105

could be sucked into the cylinder and become the cause of after-ignitions.

A fuel port *j* leads from a fuel pump to the base of the sleeve *a*, and the tube *c* has an annular recess *c'* which serves to admit the fuel from the pump to the chamber *g* formed by the inclined meeting faces of the tube *c* and the plug *b*. This supplemental air controls the richness 10 of the mixture passing through the chamber *g*. When the spindle *d* is moved upwardly, the shoulder edge *h* passes into the diverging or gradually enlarged portion of the interior of the tube *c*, which is the air 15 passage. This permits the air to flow downwardly about the spindle and to mix with the fuel mixture passing through the chamber *g* down the bore *b'*. The reduced portion *h'*, lying abreast of the converging 20 edge *i* of the tube *c*, controls the volume of air passage in proportion to the movement of the spindle *d*, in an upward direction, by increasing or decreasing the air 25 volume.

The spaced lugs *c*² prevent absolute closure of the chamber *g*, and it will be seen that the movement of the tube *c*, will not alter the air admission controlled by the spindle, as the latter will be moved correspondingly 30 to whatever position the tube *c* occupies.

Below the enlarged space *b'* the sleeve *b* and spindle *d* are provided with coöperating shoulders as indicated at *l* which act as a valve when the spindle is in its lower 35 position and which serve to further restrict and regulate the flow when the spindle *d* is raised. Near the lower extremity of the spindle *d* is a third restriction of the passage for the air and fuel caused by a lip *n* on the sleeve *b* and a shoulder *o* on the spindle *d*. Intermediate the shoulders at *l* and *o* there is a relatively enlarged passage *p*.

What I claim is:

1. A fuel injector for combustion engines, comprising in combination, a tubular sleeve, a vertically movable tube within said sleeve, provided at its lower end with an annular valve, a plug secured into said sleeve from below, provided with a valve seat for said valve, a movable regulating spindle in said tube and said plug, and a shoulder upon said spindle constituting a valve with the lower end of said tube.

2. A fuel injector for combustion engines, comprising in combination, a movable tube, a central regulating spindle therein, forming with the wall of said tube, a channel, a shoulder upon said spindle said tube being contracted on one side of said shoulder, and the inner section of the tube on the other side being diverging toward the other side of the shoulder, substantially as described.

3. A fuel injector for combustion engines, comprising in combination, a contracted,

movable tube, a central movable regulating spindle therein, adapted to contact when in its lower end-position with the contracted part of said tube, a fuel passage past the end of said tube, a shoulder on the spindle immediately below that part thereof contacting with said tube, and arranged at or near the mouth of the fuel passage said spindle being contracted below said shoulder, substantially as described.

4. A fuel nozzle for combustion engines comprising in combination, a structure comprising an outer sleeve and an inner movable tube and a socket screwed into said sleeve below said tube, said structure having an air passage delivering to the cylinder of the engine and provided with contracted portions at spaced longitudinal points thereof, and having a forced feed fuel passage delivering to the air passage at one of the contracted portions thereof, and a spindle movable longitudinally in said tube and socket and having enlargements or shoulder portions coacting with the contracted portions of said passage to vary during the movement of the spindle the cross sectional area of the air passage at more than one of the contracted portions, substantially as and for the purpose set forth.

5. A fuel nozzle for combustion engines comprising in combination, a structure comprising an outer sleeve and an inner movable tube, and a socket screwed into said sleeve below said tube, said structure having an air passage provided with gradually contracted portions at spaced points longitudinally thereof, and having a passage for fuel under pressure leading to said air passage at one contracted point thereof, and a spindle movable longitudinally in said tube and socket, said spindle having gradually enlarging portions coacting with the contracted portions to form valves and to vary during the movement of the spindle the cross sectional area of the air passage at more than one of the contracted portions, substantially as described.

6. A fuel nozzle for combustion engines comprising in combination, a structure comprising an outer sleeve and an inner movable tube and a socket screwed into said sleeve below said tube, said structure having an air passage provided with an upward and a downwardly gradually contracted portion, said structure having a forced feed fuel port delivering to said passage at the contracted point thereof, the space between said sleeve and said spindle enlarging downwardly from said first contracted portion and then again converging to form a second contracted part, and a spindle movable longitudinally in said tube and socket, and having first and second enlargements coacting with the first and second contracted points in said passage, to vary during the movements

of the spindle the cross sectional area of the air passage at more than one of the contracted portions, substantially as and for the purpose set forth.

- 5 7. A fuel nozzle for combustion engines comprising in combination, a structure comprising an outer sleeve and an inner movable tube and a socket screwed into said sleeve below said tube, said structure having an 10 air passage provided with an upper and a downwardly gradually contracting portion, said structure having a forced feed fuel port delivering to said passage at said contracted point, said passage being enlarged 15 downwardly from said first contracted point and then converging to form a second contracted point, the space between said sleeve and said spindle enlarging and down-

wardly converging at the mouth or delivering end thereof to form a third contracted point, and a spindle movable longitudinally in said tube and socket and having first, second and third enlargements coacting with the first, second and third contracted points in said passage to vary during the movements of the spindle the cross sectional area of the air passage at more than one of the contracted portions, substantially as and for the purpose set forth.

In testimony whereof I have signed my name to this specification in the presence of two subscribing witnesses.

SVEN WIGELIUS.
